PARIS GIBSON AND ALEXANDER TYLER, OF MINNEAPOLIS, MINNESOTA.

Design No. 4,012, dated May 10, 1870.

DESIGN FOR A TRADE-MARK.

The Schedule referred to in these Letters Patent and making part of the same

We, PARIS GIBSON and ALEXANDER TYLER, both of Minneapolis, in the county of Hennepin and State of Minnesota, have invented and produced a new and original Design for a Trade-Mark, of which the following is a specification.

Our design consists of a card or label having in the center a figure or representation of a five-pointed star, and having, in the five open spaces between the several points, the five letters which compose the word

north, there being one of these letters in each of the several spaces.

We claim as our invention—

The design for a trade-mark, as shown and described.

PARIS GIBSON.

ALEXANDER TYLER.
